UNITED STATES PATENT OFFICE.

JOHN F. KRCMA, OF CHICAGO, ILLINOIS.

VENDING-MACHINE.

1,168,652.

Specification of Letters Patent. Patented Jan. 18, 1916.

Application filed November 2, 1910, Serial No. 590,395. Renewed June 5, 1915. Serial No. 32,312.

To all whom it may concern:

Be it known that I, JOHN F. KRCMA, a citizen of the United States of America, and a resident of Chicago, county of Cook, State of Illinois, have invented certain new and useful Improvements in Vending-Machines, of which the following is a specification.

The main objects of this invention are to provide an improved form of vending machine; to provide improved delivery mechanism for discharging articles or packages in succession from a magazine; and to provide improved means for controlling the operation of such delivery mechanisms.

An illustrative embodiment of this invention is shown in the accompanying drawings, in which:—

Figure 1 is a side elevation of a check controlled vending machine constructed according to this invention, the casing being shown in section. Fig. 2 is a sectional elevation of the same, taken on the line A—A of Fig. 3. Fig. 3 is a sectional plan view taken on the line B—B of Fig. 1. Fig. 4 is a detail of the coin controlled releasing mechanism, as viewed from the rear. Fig. 5 is a fragmentary detail of the operating and delivery mechanisms, as viewed from the rear.

In the construction shown in the drawings, a platform 1 is supported within the casing 2 by means of a depending front part 3 and a leg 4 secured to the rear of the platform. The part 3 has lugs 5 located at opposite corners, which are adapted to be seated in suitable apertures in the base of the casing 2, whereby the platform is secured against shifting or displacement when the locking lever 6 is shifted to engage the lug 7 on the inner side of the part 3. The front 30 of the casing 2 comprises a removable frame 8, which has parts 9 adapted to fit in behind the respective shoulders 10 at the lower corners of the part 3 for securing the lower end of the front in place. A lock 11 at the 35 upper edge of the frame 8 secures the upper end of the front. The frame 8 is bowed outwardly at 12 to form a delivery chute 13 between it and the part 3. A shield 12^A is secured to the frame 8 and extends down 40 into the upper part of the delivery chute into position to prevent the delivery of more than one article or package at a time. The frame 8 has a glass panel 8^A through which the contents of the magazine 14 may be seen.

The magazine 14 is located above the platform 1, being mounted thereon, and braced

by the extension 15 of the leg 4. The magazine is made of sheet metal, and has partitions 16 which divide it into four compartments, each of which is shaped to accommodate a stack of articles or packages 17. In front of each compartment there is a spring 14^A, which is secured to the under side of the platform 1, and has its end 14^B extending up through a slot in the platform in position 60 to engage the forward end of the lowermost package, so as to prevent its displacement except through the operation of the delivery mechanism.

The delivery mechanism comprises a plurality of delivery members or striker plates 18, one for each compartment, and each is slidably mounted in a guideway 19 in the platform 1, wherein it is movable back and forth across its respective compartment. 70 The delivery members 18 are supported on the platform 1 by shoulders 20 located at the corners, and are retained in the guideways by pins 21 extending across said guideways, and bearing against the under face of the 75 platform. Springs 22, secured to the forward end of the platform 1 and to the members 18, normally urge the members into their advanced position below the magazine compartments, in which position they support the stack of packages 17. When the members are retracted, so that the front edge passes behind the rear wall of the magazine 14, the lowermost package drops onto the platform 1 into the space vacated 80 by the member 18. Upon the release of the member 18 from such retracted position, it is drawn forwardly by the spring 22, and the lowest package is discharged into the chute 13. 95

Each of the delivery members 18 has a pair of shoulders formed by lugs 23 and 24 depending from the under side thereof, and spaced apart transversely and longitudinally of the direction of travel of said members, 100 the shoulder 24 being located at the front lefthand corner (when viewed from the front) and the shoulder 23 being at the opposite edge, and to the rear of shoulder 24. A shaft 25 is rotatably mounted below the 105 platform 1 in the bearings 26, and carries a plurality of operating parts or elements 27. The elements 27 are spaced apart along the shaft 25 in position for engagement with the respective delivery members, and are arranged in different angular positions about 110 said shaft. Each of the elements 27 is in

the form of a sector, and has formed thereon a pair of oppositely disposed shoulders or lugs 28 and 29, which are respectively adapted to engage the shoulders 23 and 24 as the members 27 are rotated and move the members 18 rearwardly along the guideways 19. As the shoulders 28 and 29 are angularly spaced apart, they operate in succession to continue the rearward movement of the members 18.

10 A ratchet wheel or disk 30 is carried on the end of the shaft 25, and has notches in its periphery to form four shoulders or teeth 31, which are equally spaced. On the face of the disk are four shoulders or lugs 32, which are equally distant from the axis, and spaced apart at equal angular intervals. Pawls 33 and 34, carried by the operating lever 35, are adapted to respectively coact with the shoulders 31 and 32. As the lever 35 is oscillated, the pawls cause rotation of the disk 30 continuously in the direction indicated by the arrow in Fig. 1. The pawls 33 and 34 are pivotally connected to the operating lever 35, and are normally urged into position to coact with their respective ratchet shoulders on the disk 30 by means of a spring 36, which is connected between said pawls. The operating lever 35 is pivotally connected at 37 to the platform 1, and its end projects outwardly through a slot 38 in the front frame 6.

15 The check controlled releasing mechanism comprises a pair of members 39 and 40, mounted on the frame 8 and suitably shaped to provide between them a coin pocket below the coin chute 41, in position to receive a check therefrom. The member 39 is slidably retained on the frame 8 by and between lugs 42 and 43, near the lower end, and lugs 44 and 45 near the upper end. The member 39 has a slot 39^a which receives and engages the lever 35. A spring 46 normally urges the member 39 toward the upper limit of its 20 travel, as determined by the abutting of the shoulder 47 against the lug 44. The member 40 is pivotally connected at 48 to a flange 49 on the front of the casing, and its lower end is normally urged by the spring 50 so as to hold the detent 51 in the path of the shoulder 52 on the member 39, thus providing a limit to the downward movement of the slide member 39, unless the detent 51 is retracted. A coin pocket 53 is formed between the member 40, the edge 54 of the member 39 and a flange 55 extending upward from the lug 44, parallel with said member. The coin 56 is supported in the pocket 53 by a shoulder 57 on the member 40. The distance between the shoulder 57 and the frame 8 is less than the diameter of a coin of the proper denomination to effect the operation of the machine, and the coin is held in the position shown in dotted outline in Fig. 1 until the member 39 is moved downwardly through the opera-

tion of a lever 35. When the member 39 is so moved, the lug 58 is brought into contact with the coin 56 and urges it downwardly, so as to bear against the shoulder 57 and retract the member 40 and move the detent 51 out of the path of the shoulder 52, so as to permit a complete movement of the operating lever 35. When the coin passes the shoulder 57, it is guided by the slot 59 in the member 40 into the coin receptacle 60, and allows the member 40 to assume its normal position.

25 A double acting pawl 61 is pivoted to the frame 8 adjacent to the member 39, and urged into its intermediate position by the spring 62. The pawl 61 is adapted to engage with the rack 63, when the member 39 is moved downwardly, and prevent a return movement until after said member has completed a full stroke. When the member 39 completes its downward stroke, the pawl 61 recedes from the rack 63, and assumes its intermediate position. During the upward or return stroke of the member 39, the pawl 61 is oppositely deflected and engages with the rack 63, so as to prevent a downward movement of the member until after it has completed its return stroke.

30 The coin chute 41 is secured to the flange 49 in position to receive a coin through the slot 65. The coin chute is equipped with a magnet 66 by means of which slugs are deflected from the normal course of a proper coin, and are discharged through the space between the magnet 66 and the shoulder 67. A suitable coin, upon entering the chute, is directed by the shoulders 68, the magnet 66, and the shoulder 67, into the pocket 53.

35 The operation of the device is as follows:—A coin is inserted into the coin chute 41 and directed into the pocket 53, where it rests upon the shoulder 57. The lever 35 is depressed by the operator, and the member 39 is drawn downwardly. This movement of the member 39 brings the lug 58 into contact with the coin 56, which bears against the shoulder 57, and forces the member 40 rearwardly, and retracts the detent 51, so as to prevent its engagement with the shoulder 52 and allow the lever 35 to complete its full stroke. When the coin passes the lower end of the shoulder 57, it is deflected through the slot 59 and drops into the coin receptacle 60. As the member 39 moves down, the pawl 61 engages the rack 63 so that the member 39 must complete its stroke before it can return to its normal position. When the lever 39 completes its downward stroke, the pawl 61 recedes from the rack 63 and the member 39 is returned to its normal position by the spring 50 as soon as the operator releases the lever 35. The downward stroke of the lever 35 causes the pawl 34, which is in engagement with one of the lugs 32, to move the disk 30 a part of a rev-

olution. This movement of the lever 35 and the turning of the disk 30 brings the pawl 33 into engagement with a notch 31 so that an upward movement of the lever 35 continues the turning of the disk 30 to complete a movement thereof sufficient to cause a complete operation of the delivery mechanism. The rotation of the disk 30 causes the members 27 to be rotated, and the shoulders 28 and 29 on the members 27 are caused to coact with the shoulders 23 and 24 of the respective delivery members 18, in such manner that the delivery members 18 are made to operate in succession. A downward stroke of the lever 35, and the consequent rotation of the disk 30, brings a shoulder 28, on one of the members 27, into position to engage the shoulder 23 on the respective delivery member 18, and the subsequent upward stroke of the lever completes the engagement, and causes the partial retraction of the member 18. The next downward stroke continues the action of said shoulders, and also brings the shoulder 29 on the same member 27 into contact with the shoulder 24 on the same member 18, so that the subsequent upward stroke of the lever 35 continues the retraction of the delivery member 18, through action of the second pair of shoulders. The next downward stroke of the lever 35 completes the retraction of the delivery member 18, and the lowermost package 17 drops into the space vacated by the delivery member 18. The subsequent upward stroke of the lever 35 causes the shoulder 29 to recede from the shoulder 24, and the spring 22 urges the delivery member 18 into its advanced position, whereupon the package is discharged from the compartment into the delivery chute 13. Thus it requires three complete oscillations of the lever 35 to effect one complete operation of any one of the delivery members 18, but the four operating members 27 are so arranged with respect to each other that they operate in succession, and release one of the delivery members for each complete operation of the lever. Thus, articles are delivered from the different magazine compartments in rotation.

Although but one specific embodiment of this invention is herein shown and described, it will be understood that numerous details of the construction shown may be altered or omitted without departing from the spirit of this invention, as defined by the following claims.

I claim:—

1. In an ejecting mechanism of the class described a table for supporting the articles to be ejected, a rotatable shaft therebeneath, a plurality of cams thereon, slidable striker plates on said table, a pair of downwardly extending offset arms on each plate, said cams arranged in pairs and in offset relation

on said shaft adapted to contact said arms successively to retract said plates, and a spring adapted to impel each plate forwardly when released from said arms to strike a sharp blow on the lowermost article of a pile to eject the same. 70

2. In a device of the class described a table for supporting the articles to be vended in piles, striker plates on said table adapted to strike a hammer blow on the lowermost article of a pile to discharge the same therefrom, spring fingers adapted to retain the lowermost article from discharge until impelled by said striker plate, depending arms on each of said striker plates arranged in offset relation, a shaft beneath said table, cams thereon, a pair for each striker plate arranged in offset relation, each adapted to contact one of said depending arms in successive order to retract the striker plate, and a spring adapted to impel the striker plate forwardly to strike the article to be discharged. 75 80 85

3. In a device of the class described a table for supporting the articles to be vended in piles, striker plates on said table adapted to strike a hammer blow on the lowermost article of a pile to discharge the same therefrom, means adapted to retain the lowermost article from discharge until impelled by said striker plate, arms on each of said striker plates arranged in offset relation, a cam shaft beneath said table, adapted to actuate said arms in successive order to retract the striker plate, and resilient means adapted to impel the striker plate forwardly to strike the article to be discharged. 90 95 100

4. A device of the class described embracing a supporting table, means supporting a plurality of piles of articles thereon for vending, a plurality of discharge plates adapted to be actuated in successive order to discharge the lowermost article of each pile, a pair of arms adapted to retract each discharge plate, and to retain said plate in retracted position for an instant before releasing the same, and means impelling said plate forwardly to strike said article a sharp blow to eject the same. 105 110

5. In a device of the class described a table, a plurality of compartments supported thereon to receive piles of articles to be vended, plates slidable on said table at the bottom of each compartment and normally supporting the pile of articles therein, means retracting said plates in successive order to permit the pile to rest on said table, and a spring adapted to impel said plate forwardly to strike the lowermost article from said pile and permit the pile to rest on said plate. 115 120

6. A device of the class described embracing a table, means supporting a plurality of piles of articles thereon for vending, a plurality of discharge plates adapted to be actu- 125 130

ated to discharge the lowermost article of each pile, cams adapted to retract each discharge plate, and to retain said plate in retracted position for an instant before releasing the same, and a spring impelling said plate forwardly to strike said article a sharp blow to eject the same.

7. In a vending machine, the combination of a casing, a platform mounted therein, a magazine above said platform, a striker plate slidably mounted on said platform and adapted to be moved back and forth across said magazine for discharging packages therefrom, means normally urging said striker plate into its advanced position, a pair of shoulders on said striker plate spaced apart longitudinally of the direction of travel of said striker plate, a rotatable element having a pair of angularly spaced shoulders respectively adapted to engage said other shoulders in succession when said rotatable element is operated for retracting said striker plate, and means for rotating said rotatable element.

25 8. In a vending machine, the combination of a casing, a platform mounted therein, a magazine above said platform, a striker plate slidably mounted on said platform and adapted to be moved back and forth across said magazine for discharging packages therefrom, means normally urging said striker plate into its advanced position, a pair of shoulders on said striker plate spaced apart laterally and longitudinally of the direction of travel of said striker plate, a rotatable element having a pair of angularly spaced shoulders respectively adapted to engage said other shoulders in succession when said rotatable element is operated for retracting said striker plate, and means for rotating said rotatable element.

30 9. In a vending machine, the combination of a casing, a platform therein, an article magazine supported by said casing and com-

45 prising a plurality of compartments, a plurality of striker plates, one for each of said compartments, slidably mounted on said platform and adapted to be moved back and forth across said magazine for discharging articles therefrom, means normally urging said striker plates into their advanced 50 position, a shoulder on each of said striker plates, a shaft transverse to the paths of said striker plates, a plurality of rotatable members, one for each striker plate, mounted on said shaft and spaced apart angularly and laterally, and adapted, when said shaft is rotated, to successively engage the respective shoulders on said striker plates, so as to retract and release said striker plates in 55 succession, and means for rotating said shaft.

10. In a vending machine, the combination of a casing, a platform therein, a magazine supported by said platform, a striker plate mounted on said platform and adapted to be moved back and forth across said magazine for discharging packages therefrom, a shoulder on said striker plate, a shaft having a shoulder carried thereby and 60 adapted to engage the first said shoulder for retracting said striker plate, a disk carried by said shaft, a plurality of notches on the periphery of said disk, a plurality of shoulders on the face of said disk, an operating lever, a pair of pawls carried by said lever and normally urged into position to respectively engage said notches and shoulders, whereby when said lever is oscillated, said pawls will cause said disk to rotate continuously in one direction.

Signed at Chicago this 31st day of October, 1910.
